United States Patent Office

Des. 207,268
Patented Mar. 28, 1967

207,268

TOY CANNON

Maurice Rosenbloom, Fort Lee, N.J., assignor to De Luxe
Reading Corporation, a corporation of New Jersey

Filed Apr. 19, 1966, Ser. No. 1,935

Term of patent 3½ years

(Cl. D34—15)

F/6.1

FIG. 3

I claim:

The ornamental design for a toy cannon, substantially as shown and described.
